HEEL SEAT FITTING MACHINE

Frank Barton, Leicester, England, assignor to
United Shoe Machinery Corporation, Paterson, N. J., a corporation of New Jersey

Application May 26, 1932, Serial No. 613,653.
In Great Britain June 16, 1931. Renewed May
11, 1934

29 Claims. (Cl. 12—31.5)

This invention relates to machines for operating upon soles and is illustrated as embodied in a machine for trimming the rear portions of soles for the reception of heels.

It is sometimes the practice to fit the heel seats of soles for receiving heels such, for example, as wood heels of women's shoes, prior to the attachment of the soles to their respective shoe uppers. A machine which may be used successfully for this purpose is disclosed in British Letters Patent No. 305,276 and comprises a matrix plate having an opening formed therein and a work supporting plunger located directly beneath the opening and upon which the heel end of an unattached sole may be positioned, the plunger being mounted for movement to force the heel seat part of the rear portion of the sole through the opening and above a face of the matrix plate. After the sole has been properly distorted, portions of the sole lying below the face of the plate are trimmed from the sole by a knife, the cutting edge of which moves over the face of the plate, thereby to provide a heel seat of substantially the same size as the opening formed in the plate.

An object of this invention is to provide an improved machine of the general type above described. In fitting the heel seats of soles of shoes, it is desirable to vary the sizes of the heel seats in accordance with variations in the sizes of the attaching faces of the heels which are to be secured to the shoes. Hence, the illustrated machine, in accordance with a feature of the invention, is provided with matrix plates which are relatively adjustable to vary the size of a U-shaped opening formed by the plates, according to the size of the heel seat desired, and a plunger comprising a member for clamping a sole against the plates and a bulger having a sole engaging face mounted for movement to force the heel seat portion of the clamped sole through the opening and beyond faces of the plates, and a cutter mounted for movement over the faces of the plates to remove the margins of the heel seat portion of the sole from the sole. The illustrated plunger is constructed and arranged to receive interchangeably one of a plurality of bulgers the sole engaging faces of which are of different sizes and shapes.

By providing a plunger constructed interchangeably to receive one of a plurality of bulgers having sole engaging faces of various sizes and shapes, the operator may readily select a bulger which will effectively cooperate with the matrix plates when adjusted to fit a heel seat of a de-

sired outline, to form a predetermined bevel around the marginal portion of the heel seat.

In the illustrated construction the clamping members are U-shaped and have upper beveled faces which, when the plunger is raised, engage complementary beveled faces formed on the matrix plates. In order to insure that the beveled faces of the clamping members will cooperate with the beveled faces of the plates when fitting heel seats of various sizes, the clamping members and the matrix plates are mounted for adjustment together and to the same extent.

The illustrated machine is provided with a gage which is shaped and arranged to centralize the rear portion of the sole and is movable against a stop under pressure of a sole to position the same lengthwise in the machine. In order to remove surplus material which has been trimmed from the sole from the operating parts of the machine, and in accordance with a further feature of the invention, the gage of the illustrated machine is automatically operated in timed relation with the plunger for movement over the sole supporting surface of the plunger after the plunger has been moved to a predetermined position away from the matrix plates.

In order to expedite the heel seat fitting operation and to permit the operator freely to use both hands during such operation, the illustrated machine is provided with a single member shown as a treadle and operable to raise the plunger thereby distorting the sole and then automatically to trip a clutch which causes the cutter to move over the surface of the matrix plates to trim the sole.

These and other features of the invention will now be described with reference to the accompanying drawings, in which

Figs. 1 and 2 show side and plan views respectively of the illustrated machine, portions of which have been broken away in order better to show the construction thereof;

Fig. 3 is a perspective view of a plunger of the illustrated machine;

Fig. 4 is a longitudinal vertical section of a portion of the machine, and shows a sole the rear part of which is being trimmed in the machine;

Fig. 5 is a sectional view taken along line V—V of Fig. 4;

Fig. 6 is a sectional view of the plunger taken along the line VI—VI of Fig. 4; and

Fig. 7 is a perspective view of the rear part of a sole, the heel seat portion of which has been trimmed in the illustrated machine.

The illustrated machine is described with ref-

110

erence to the performance of the heel seat fitting operation on unattached soles, shaping the heel portion of a sole 20 to provide a tongue 22 (Fig. 7) shaped to be received within the concave attaching face or "cup" of a Louis heel, and forming a pair of transversely extending shoulders 21 upon which the front portion or "lip" of the heel is rested. The illustrated machine comprises matrix plates 24 mounted for movement toward and away from each other and shaped to provide a U-shaped opening 26 (Fig. 2) through which the heel seat portion or tongue 22 of a sole positioned in the machine by a gage 28 is forced by a plunger 27, the portion of the sole remaining below upper faces 30 of plates 24 (Fig. 4) being severed from the sole by a cutter or knife 32, the cutting edge 34 of which is mounted for movement along the upper faces 30 of the plates 24.

The operating parts of the illustrated machine are mounted in a main frame 36 secured to a suitable support (not shown) and provided with a curved guideway 38 shaped to receive curved T-shaped depending blocks 40 one of which is secured through screws 41 (Fig. 2) to each of the matrix plates 24. The forward inner corners of the plates 24 are cut away to provide the U-shaped opening 26 which has the same general outline as the heel seat of a sole to be fitted in the machine. The plates 24 are undercut around the opening 26 to form side faces or walls 42 (Fig. 1) of the opening which are shaped to allow the central portion of the heel end of the sole to be forced by the plunger 27 through the opening 26 with a minimum amount of distortion of the sole.

The curved guideway 38 of the casting 36 is concentric with reference to point 44 (Fig. 2) which is located at the extreme end of the opening 26 formed by the plates 24 and about which the plates 24 may be adjusted at equal distances from and at opposite sides of a central plane 46 (Fig. 2) of the machine. In order to adjust the plates 24 about the point 44 each of the plates 24 is provided with a depending pin 48 (Fig. 1) pivotally secured thereto and in threaded relation with a transversely extending horizontal screw 50 rotatably mounted in the casting 36 and threaded in opposite directions along different portions thereof. Upon rotation of the screw 50 through a hand wheel 52 (Fig. 2), the plates 24 may be pivotally adjusted about point 44 as the blocks 40 screwed to the plates 24 are moved along the curved guideway 38 to increase or to decrease the size of the opening 26 which is formed between the plates 24 and which determines the size to which the heel seat of the sole is to be trimmed by the machine. To assist in guiding the plates 24 as they are pivotally adjusted, the extreme forward end portions of the plates are provided with slots 53 (Fig. 2) which are concentrically arranged with respect to the point 44 and through which extend studs 58 secured to the casting 36.

The work supporting plunger 27, which is constructed to receive interchangeably one of a series of bulgers 54 of different sizes and has an upper sole engaging face 60, is mounted in a vertical guideway 62 (Fig. 1) of the frame 36 and is located directly below the opening 26. The face 60 of the illustrated bulger 54 is slightly beveled at its marginal portions. In order, however, to make a more pronounced bulge at the rear end of the portion of the sole forced above the faces 30 of the plates 24, the rear edge of the bulger may

be disposed substantially at right angles to the face 60.

The chosen one of the interchangeable bulgers 54 may be conveniently mounted upon and secured to a vertically disposed slide 64 of the plunger 27 through the tongue and groove arrangement 65 (Fig. 5). A latch 66 which is pivotally mounted upon a pin 68 carried by the slide 64 locks the bulger 54 to the slide 64, the latch normally being urged upwardly by a spring 85 pressed plunger 70 inserted in a recess of the slide to cause a projection 74 of the latch to engage a recess 76 of the bulger 54. The slide 64 is enclosed within a sleeve 78 (Fig. 1) and is in threaded relation with a rod 80 and is also in engagement with a flanged portion 79 of the rod upon which is mounted an adjustable hand wheel 82. The sleeve 78 is supported at its lower end by a head 84 which is held in engagement with the sleeve 78 by a spring 86 encircling the rod 80 and having its upper and lower ends in engagement with the head 84 and the hand wheel 82 respectively. It will be noted that as the slide 64 is moved upwardly (Fig. 1) by a lever 88 pivoted on the casting at 90 and having a ball portion 92 shaped and positioned to engage a recessed portion 94 of the slide 64, the sleeve 78 will be moved upwardly with the slide until its free movement therewith is impeded as will later be described.

The sleeve 78 has a head 96 upon which is mounted a pair of curved clamping members 98, 100 which are pivotally secured to the head by a pin 102, an end portion of which is in threaded relation with clamp member 100. The pin 102 is provided with a cylindrical portion 104 of suitable size to fit within a recess in the clamp member 98, the members being assembled on the head 96 by inserting the pin 102 in an enlarged opening 106 at the under side of the head 96 and by then screwing the pin into the clamp member 100. The clamp members 98, 100 taken together are U-shaped and surround the bulger 54 as well as conform generally to the outline of the face 60 of the bulger.

It is desirable that the sole 20 be clamped firmly between the plates 24 and the clamp members 98, 100 as the bulger 54 is raised to move the heel seat portion 22 of the sole above the faces or surfaces 30 of the plates 24. Accordingly, the clamping members 98, 100 have upper beveled faces 108 which cooperate with the beveled faces 42 of the matrix plates 24 to clamp the sole through the spring 86 and the mechanism above described, while the slide 64 which carries the bulger 54 is being raised. The bulger 54, which is mounted upon the slide, is moved upwardly until its face 60 lies very slightly below the plane of the upper faces 30 of the matrix plates 24. Upward movement of the bulger 54 is terminated by a stop 110 adjustably mounted in the main frame 36 of the machine and positioned to engage the lever 88 when the face 60 of the bulger 54 arrives at a position slightly below the faces 30 of the plates 24.

In order to fit the heel seat portions of different soles for the reception of heels of different sizes and styles, tongues 22 of different shapes will be required. It is therefore desirable that the matrix plates 24 be adjusted relatively to each other to provide openings of different sizes. When the size of the opening 26 is changed by pivotally adjusting the plates about point 44, it is generally desirable to position on the slide 64 a bulger 54, the face 60 of which has an outline of the same general shape as the opening 26 but spaced from 150

the edges of the plates 24 at a distance approximately equal to the thickness of the sole being trimmed. In order to insure that the upper faces 108 of the clamping members 98, 100 will engage the beveled faces 42 of the plates for different adjusted positions of the plates and in order to construct the clamp members 98, 100 so that they will receive bulgers 54 of various sizes and will conform generally to the outlines of the faces 60 10 of different bulgers, the members 98, 100 are mounted for adjustment about a pin 102 the axis of which passes through point 44.

In order to adjust the clamping members 98, 100 toward and away from one another each of 15 the matrix plates 24 is provided with a depending pin 112 which fits into a cylindrical opening of a laterally extending flange 114 of a corresponding clamping member, each of the clamp members 98, 100 being guided for pivotal adjustment by a 20 screw 116 (Fig. 3) secured thereto and having an enlarged head shaped to engage an undercut circular guideway 118 formed in the head 96.

When the plunger 27 is out of engagement with the matrix plates 24 (Fig. 1) the upper surfaces 25 108 of the members 98, 100 are located slightly above the plane of the face 60 of the bulger 54, such adjustment being effected by the spring 86 which forces the head 84 and the sleeve 78 upwardly with respect to the slide 64 until the 30 head 84 engages the flanged portion 79 of the rod 80. The above adjustment permits the clamp members 98, 100 to force the sole against the plates 24 before the bulger 54 starts to cooperate with the plates to distort the sole. It will be 35 noted that when the plunger 27 is in its lowered position, the clamp members 98, 100 are located beneath the lower surface of the gage 28 which, as will later be explained, serves as an ejector for removing portions trimmed from the sole 40 from the machine.

In order to trim from the distorted sole 20 (Fig. 4) material lying below the upper faces 30 of the plates 24, the cutting edge 34 of the knife 32 is mounted for movement in contact with the faces 30 of the plates 24. The knife 32 is secured between a carrier 120 and a clamp 122 by a screw 124. The carrier 120 is guided for reciprocation in horizontally disposed forwardly and rearwardly extending grooves 126 formed 50 in the frame of the machine and is pivotally connected to a rearwardly extending link 128 which is secured to an eccentric (not shown) connected to a one-revolution clutch (not shown).

In order to operate the lever 88 (Fig. 1) a 55 housing 130 is pivotally secured to the same and encloses a spring 132, which is supported on a column 134 screwed into the lower end of the housing 130 and has its upper end in engagement with a head portion 136 of a treadle rod 138. To insure that the plunger 27 will effectively press the heel seat portion of the sole 20 through the opening 26 formed in matrix plates 24, the spring 132 is of substantial strength.

For assisting the operator in positioning the sole 20 relatively to the plunger 27 and to the opening 26 formed in the matrix plates 24, the 65 illustrated machine is provided with the work gage 28 which is positioned below the matrix plates 24. The gage 28 comprises a flat bar 140 extending forwardly and rearwardly of the machine and has at its forward end a bifurcated portion 142 which centralizes the rear part of the sole in the machine and is located slightly rearwardly of and just above the plunger 27 (Fig. 1) when the same is in its lowered position.

To position the sole 20 lengthwise in the machine, the gage 28 is provided with a depending portion 144 which may be moved rearwardly against an adjustable stop 146 mounted in the machine frame, the depending portion 144 being normally held slightly forwardly of the stop 146 by a spring 148, one end of which passes through the depending portion 144 and the other end of which is screwed to the frame of the machine.

The gage 28, in addition to locating soles in the machine, serves as an ejector to push waste material, which has been trimmed from the sole and usually rests upon the plunger 27, from the machine. In order to operate the gage 28 for this purpose, the rear end of the gage is provided with bifurcations 150 each of which carries a threaded stud 152 upon which is mounted a pawl 154 free to swing in a rearward direction about the stud 152 but prevented from moving in a forward direction because of contact between a face 156 (Fig. 1) of the pawl 154 and a cooperating face 158 of the corresponding bifurcation 150.

To move the gage 28 forwardly of the machine against the pressure of the spring 148 to eject from the machine chips trimmed from the sole, the machine is provided with a bifurcated link 160 pivotally mounted on a shaft 162 extending transversely of the machine at its rear portion. The link 160 carries projecting pins 164 at its upper ends, the pins 164 being constructed and arranged to engage respective pawls 154 at predetermined intervals to move the gage 28, which may also be referred to as an ejector or a combined gage and ejector, forwardly of the machine. To operate the link 160, the latter has connected to it a tensioning spring 166 which extends forwardly of the machine and is secured at its forward end to a pin 168 fixed to the machine frame. In order to move the bifurcated link 160 to a position rearwardly of the pawls 154 the lever 88 is provided with a rearward extension which carries a stud 170 arranged to engage forward faces 172 of the link as the treadle rod 138 is moved downwardly to raise the plunger 27. The stud 170 carried by the lever 88 causes the link 160 to move in a rearward direction about its shaft 162 to position the pins 164 behind the pawls 154 of the gage 28, the pawls moving freely on the studs 152 as the 110 pins 164 swing rearwardly.

To hold the bifurcated link 160 at its rearward-most position until the plunger 27 has been lowered to a position in which the upper beveled faces 108 of the members 98, 100 are located slightly below the bottom face of the gage 28, a forwardly extending finger 174 is freely mounted on a rod 176 which extends transversely of the machine. The finger 174 is provided at its under side with a notch 178 for engaging an extension 180 carried by the bifurcated link 160, when the latter has been urged rearwardly by the pressure of the lever 88, and thus maintaining the link 160 in its rearward position until the finger 174 is lifted. The finger 174, which is normally urged 120 downwardly by a spring 182, is lifted as the rod 138 is allowed to rise by the stud 170 carried by the lever 88, the stud 170 operating against the forward end of the finger 174 to lift it away from engagement with the extension 180 of the bifurcated link 160. As soon as the lever 88 is lifted 130 to release the bifurcated link 160, the latter moves forwardly of the machine about the shaft 162 to strike against the pawls 154 thereby causing the gage to move forwardly of the machine 135

5

to eject from the machine a sole trimming or chip which rests on the plunger 27. The treadle rod 138 is normally held in raised position, the upward movement of the same being limited by a stop 184 adjustably mounted upon the lever 88 and positioned for engagement with the machine frame. The stop 184 is adjusted to engage the machine frame, when the beveled portions 108 of the members 98, 100 have been lowered to a position 10 slightly below the under surface of the gage 28. The one-revolution clutch (not shown) which actuates the cutter or knife 32 may be tripped by hand if desirable but, in order to expedite the trimming operation and to enable the operator 15 freely to use both hands in presenting work to the machine, the illustrated machine is provided with an automatic trip device for the clutch (not shown). The operation of the clutch is controlled by the treadle rod 138, the head 136 of the rod being provided with a pin 186 which, after the plunger 27 has been raised to urge the work into correct position relatively to the opening 26 formed by the matrix plates 24, engages a step 188 of a lever 190 which is pivoted on the shaft 162 and has at its rear end a slot 192 shaped to receive a block 194 mounted upon an arm 196 which is secured to the shaft 176. Upon the shaft 176 is another arm 198 to which is pivotally secured a link 200 for tripping the clutch. 20 The degree of adjustment of the matrix plates 24 necessary to provide an opening 26 of a suitable size to form a tongue of a desired size may be readily determined by providing one of the plates 24 with an index mark 202 (Fig. 2) which 25 may be swung into alignment with one of a plurality of size marks of a scale 204 cut in the machine frame. In order to trim the rear portion of the sole to 30 form the heel seat portion 20 which may also include the shoulders 21, the operator places the heel end of the sole upon the top face of the plunger 27 flesh side up and forces the rear end of the sole against the bifurcated portion 142 of the gage 28, to centralize the sole and at the same 35 time pushes the gage rearwardly against the stop 146 to position the sole lengthwise. The treadle rod 138 is then lowered to raise the plunger 27 for forcing the sole through the opening 26. As the plunger 27 is raised the clamping members 98, 100 40 are forced against and cooperate with the beveled faces 42 of the matrix plates 24 to clamp the sole as the bulger continues its upward movement to push the sole through the opening 26 and above the upper faces 30 of the matrix plates. When 45 the face 60 of the bulger 54 arrives at a position very slightly below the level of the faces 30 of the plates 24, further upward movement of the bulger is prevented by contact of the lever 88 with the stop 110. Upon further upward movement 50 of the treadle rod 138, the pin 186 engages the step 188 of the lever 190 to trip through the above-described mechanism the one-revolution clutch (not shown) which actuates the knife 32 to cause 55 the same to move over the plates 24 to trim from the sole portions of the same which are located below the faces 30 of the matrix plates 24. In the meanwhile the bifurcated link 160 is moved 60 through the above-described mechanism rearwardly of the machine to a position behind the pawls 154 of the gage 28. After the sole has been trimmed and the plunger 27 has been lowered to a position below the gage 28, the link 160 is released and strikes the pawls 154 to move the gage 65 28 forwardly of the machine to push from the

machine a chip which has been removed from the sole and which is located on the plunger 27.

Having thus described my invention, what I claim as new and desire to secure by Letters Patent of the United States is:

1. A heel seat fitting machine having, in combination, matrix plates provided with sole engaging faces which are arranged at one side of the plates and define a U-shaped opening, means for relatively adjusting the plates thereby to vary the shape of the opening, a plunger, a bulger carried by the plunger and having a U-shaped sole supporting face, said bulger being mounted for movement to force the central part of the heel seat portion of the sole of a shoe through the opening and beyond the other side of the plates, and a knife mounted for movement along said other side of the plates to remove the margins of the heel seat portion of the sole, said plunger being constructed and arranged interchangeably to receive one of a plurality of bulgers having sole supporting faces of different shapes.

2. A heel seat fitting machine having, in combination, plates constructed and arranged to provide a U-shaped opening and mounted for relative adjustment to vary the shape of the opening, a plunger carrying members to clamp a sole against the plate and a presser foot to force the heel seat portion of the sole through the opening and beyond faces of the plates while the sole is so clamped, said members being mounted for adjustment relatively to each other to permit them to be adjusted in accordance with adjustments of the plates, and a cutter to trim off the clamped marginal portion at the heel end of the sole thereby fitting the sole for the reception of a heel.

3. A heel seat fitting machine having, in combination, matrix plates mounted for relative adjustment and constructed and arranged to provide an opening, a plunger having members mounted for relative adjustment and forming a clamp constructed and arranged to press the heel portion of a sole against the plates and also comprising a presser foot to force the heel seat portion of the sole through the opening and beyond faces of the plates, and a cutter to trim off the clamped marginal portion at the heel end of the sole thereby fitting the sole for the reception of a heel.

4. A heel seat fitting machine having, in combination, matrix plates mounted for pivotal adjustment toward and away from a central plane and constructed and arranged to provide an opening, a plunger provided with members pivotally adjustable toward and away from the central plane and constructed and arranged to press the heel seat portion of a sole against the plates and also provided with a presser foot to force the heel seat portion of the sole through the opening and beyond faces of the plates, and a cutter to trim off the clamped marginal portion at the heel end of the sole thereby fitting the sole for the reception of a heel.

5. A heel seat fitting machine having, in combination, matrix plates constructed and arranged to provide an opening and mounted for relative adjustment to vary the size of the opening, a plunger comprising members mounted for relative adjustment and forming a clamp constructed and arranged to press the heel portion of a sole against the plates and also comprising a presser foot to force the heel seat portion of the sole through the opening and beyond the plates, a cutter to trim parts of the sole lying beneath said faces to fit the sole to receive the attaching face

- of a heel, and mechanism to move the plates and the members to correlated positions to insure that the members will cooperate effectively with the plates in pressing the heel portion of the sole 5 against the plates for different adjusted positions of the same. 80
6. A heel seat fitting machine having, in combination, matrix plates mounted for adjustment toward and away from a central plane and constructed and arranged to provide an opening, a plunger carrying clamping members pivotally adjustable toward and away from the central plane and constructed and arranged to press the rear portion of a sole against the plates and also provided with a presser foot to force the heel seat portion of the sole through the opening and beyond faces of the plates, a cutter to trim off the clamped marginal portion at the heel end of the sole thereby fitting the sole for the reception of a heel, and connections between the plates and the clamping members to cause an adjustment of one to effect an adjustment of the other. 90
7. A heel seat fitting machine having, in combination, plates having opposed faces mounted for adjustment toward and away from each other and forming a U-shaped opening, a plunger movable relatively to the plates to force the central part of the rear portion of a sole through the opening and beyond faces of the plate, said plunger carrying a bulger face similar in shape to the opening and peripheral portions adjustable relatively to each other and constructed and arranged to cooperate with the plates in clamping the sole as the bulger face forces the sole 100 through the opening, and a cutter movable along the plates to trim off portions of the sole lying beneath said faces to fit the heel seat portion and the sole for the reception of a heel. 105
8. A heel seat fitting machine having, in combination, plates constructed and arranged to provide a U-shaped opening and mounted for relative adjustment to vary the shape of the opening, a plunger comprising members adjustable with respect to each other to clamp a sole against the 110 plate and a presser foot to force the heel seat portion of the sole through the opening and beyond the plates while the sole is so clamped, mechanism connecting the plates and the members to adjust the members upon adjustment of the plates, and a cutter to trim off the clamped marginal portion at the heel end of the sole thereby fitting the sole for the reception of a heel. 115
9. In a heel seat fitting machine, a plunger 120 comprising a sole bulging plate and clamp members which are positioned adjacent to the plate and are mounted for relative adjustment, and means constructed and arranged for cooperation with the plunger to cause the members to clamp the heel seat portion of a sole and then to cause said plate to distort said clamped heel seat portion.
10. In a heel seat fitting machine, a plunger 125 constructed and arranged interchangeably to receive one of a plurality of sole bulging plates each of which has a sole engaging face, and carrying clamp members having sole engaging portions positioned laterally of the face of the plate located on the plunger and yieldable under pressure with respect to the plate, said members being mounted for relative adjustment with relation to said plate. 130
11. In a heel seat fitting machine, a plunger 135 constructed and arranged interchangeably to receive one of a plurality of sole bulging plates each of which has a U-shaped sole engaging face, and carrying a U-shaped clamp including a plurality of parts surrounding the U-shaped face of the plate and having sole engaging portions normally extending above said face, said parts being relatively adjustable. 140
12. In a heel seat fitting machine, a plunger 145 constructed and arranged interchangeably to receive one of a plurality of sole bulging plates each of which has a sole engaging face, said plunger carrying a U-shaped clamp including two parts surrounding the U-shaped face of the plate mounted upon the plunger and having sole engaging portions normally extending above said face and yieldable under pressure relatively to said face, said parts being mounted for pivotal adjustment relatively to each other. 150

- constructed and arranged interchangeably to receive one of a plurality of sole bulging plates each of which has a U-shaped sole engaging face, said plunger carrying a U-shaped clamp including a plurality of parts surrounding the U-shaped face of the bulging plate mounted upon the plunger and having sole engaging portions normally extending above said face and yieldable under pressure relatively to said face, said parts being pivotally mounted upon the plunger and adjustable laterally of the U-shaped face. 6 80
19. A heel seat fitting machine having, in combination, relatively adjustable plates forming with each other an undercut opening, a plunger carrying relatively adjustable members to clamp a sole against the undercut wall of the opening and a bulger to force the heel seat portion of the sole through the opening and beyond said faces of the plates, mechanism to impart relative movement to the members upon relative movement of the plates, and a cutter constructed and arranged to move along said faces to trim off the clamped marginal portion at the heel end of the sole thereby fitting the sole for the reception of a heel. 15 85
20. A heel seat fitting machine having, in combination, matrix plates relatively adjustable toward and away from a central plane and provided with a U-shaped opening the side of which is undercut, a plunger comprising members mounted for adjustment toward and away from the central plane and arranged to clamp a sole against the undercut wall of the opening and also comprising a bulger to force the heel seat portion of the sole through the opening and beyond faces of the plates, mechanism to effect relative adjustment of the members upon relative adjustment of the plates, and a cutter constructed and arranged to move along said faces of the plates to trim from the sole the portion thereof lying beneath the faces to fit a heel seat portion of the sole. 25 90
21. A heel seat fitting machine having, in combination, plates mounted for pivotal adjustment relatively to each other and formed together to provide a U-shaped opening, a plunger carrying clamp members mounted for pivotal adjustment and together forming a U-shaped clamp constructed and arranged to press a heel portion of a sole against the plates around the opening and also carrying a bulger to force the heel seat portion of the sole through the opening, mechanism to adjust the plates relatively to each other, and connections to constrain each of the clamp members and the corresponding plate for movement together to insure that the same portions of the members and the plates will cooperate in clamping the sole for different adjusted positions of the plates. 40 95
22. A heel seat fitting machine having, in combination, plates mounted for pivotal adjustment relatively to each other and formed to provide a U-shaped opening, a plunger comprising clamp members mounted for pivotal adjustment and forming a U-shaped clamp constructed and arranged to press a heel portion of a sole against the plates around the opening and also comprising a bulger to force the heel seat portion of the sole through the opening, and mechanism to cause pivotal adjustment of each of the plates together with the corresponding clamp member to insure that the clamp members will cooperate with the same portions of the plates to clamp the sole for different adjustments of the plates. 60 100
23. In a heel seat fitting machine, a movable plunger constructed and arranged interchangeably to receive one of a plurality of bulger plates having U-shaped sole engaging faces of different sizes, a pair of matrix plates formed to provide a U-shaped opening for receiving one of the plates and mounted for relative pivotal adjustment to vary the shape of the opening in accordance with the size of the bulger plate positioned on the plunger, said plunger carrying a pair of pivotally adjustable members having a general U-shape and constructed and arranged to clamp the sole against the plates upon movement of the plunger toward said plates, connections between the plates and the members to cause the same to be pivotally adjusted simultaneously, and means to operate the plunger. 105 105
24. A heel seat fitting machine having, in combination, a plunger constructed and arranged interchangeably to receive one of a plurality of sole bulging plates each of which has a sole engaging face, matrix plates having opposed faces formed to provide a U-shaped opening and mounted for adjustment toward and away from each other to vary the size of the opening in accordance with the size of the heel seat to be fitted, said plunger comprising a U-shaped clamp including a plurality of adjustable parts surrounding the sole engaging face of a bulging plate positioned upon the plunger and having sole engaging portions normally extending beyond the face of said bulging plate, mechanism to move the plunger to cause the clamp to force a sole mounted upon the plunger against the opposed faces of the matrix plates and then to cause the bulging plate to force a portion of the sole through the U-shaped opening and beyond surfaces of the matrix plates, and a cutter mounted for movement upon said surfaces to sever from the sole portions thereof lying beneath said surfaces to shape the sole for receiving an attaching face of a heel. 110 110
25. In a heel seat fitting machine, mechanism to trim the rear part of a sole to fit the heel seat portion thereof for the reception of a heel, a stop, a combined gage and chip ejector movable under pressure of the sole against the stop, and mechanism to move the ejector forwardly of the sole after each trimming operation thereby to remove from the machine trimmings severed from the sole. 115 120
26. In a heel seat fitting machine, a member comprising a combined gage and chip ejector, resilient means normally to retain the member forwardly of its gaging position to permit the same to centralize the rear portion of a sole in the machine as the sole moves the member rearwardly, means constructed and arranged to trim material from the rear portion of the sole to fit the same for receiving a heel, and mechanism operating in timed relation with said means to move said member forwardly to eject a chip trimmed from the sole from the machine. 125 130
27. In a heel seat fitting machine, a movable gage shaped to centralize the rear portion of a sole in a machine, a stop to limit movement of the gage under pressure of the sole to position the sole lengthwise, mechanism normally to position the gage away from the stop in order to permit the sole in engagement with the gage to be centralized as it is positioned lengthwise, means constructed and arranged to trim material from the rear portion of the sole positioned in the machine, and mechanism operating in timed relation with said means to move the gage away from the 135 140
- 75 145
- 75 150

stop to eject from the machine the portions trimmed from the sole

28. A heel seat fitting machine having, in combination, a matrix plate provided with an opening, 5 a plunger mounted for movement toward and away from the plate, said plunger comprising members for clamping the heel seat portion of the sole of a shoe against the plate and a bulger movable relatively to said members for forcing the 10 central part of the heel seat portion of the sole through the opening and beyond a surface of the matrix plate while said portion is clamped, a cutter mounted for movement over the surface of the plate to trim marginal portions at the heel end of 15 the sole thereby to fit the sole for the reception of a heel, and a common operating member constructed and arranged first to raise the plunger to cause the same to cooperate with the matrix plate for distorting the heel seat portion of the sole and 20 then to cause the cutter to remove the margins of the heel seat portion of the sole.

29. A heel seat fitting machine having, in combination, a plate provided with an opening, a plunger mounted for movement toward and away from the plate and having a surface to force a sole through the opening and beyond a face of the plate, a cutter mounted for movement over the face of the plate to trim from the sole portions thereof lying below said face of the plate, a stop to limit the movement of the plunger toward the plate, an operating rod, a lever connected to the rod and movable into engagement with the stop to raise the surface of the plunger in substantial alignment with said face of the plate, and yielding mechanism to permit continued movement of the rod after engagement of the lever with the stop to cause the rod to operate the cutter to cause it to move over the face of the plate to trim the sole.

FRANK BARTON.
